Patented July 18, 1922.

2 SHEETS—SHEET 2.

UNITED STATES PATENT OFFICE.

CHARLES D. BONSALL, OF PARNASSUS, PENNSYLVANIA, ASSIGNOR TO WALTER P. MURPHY, OF NEW YORK, N. Y.

REINFORCED CAR END-WALL STRUCTURE.

1,422,823.

Specification of Letters Patent. Patented July 18, 1922.

Application filed November 14, 1919. Serial No. 338,075.

To all whom it may concern:

Be it known that I, CHARLES D. BONSALL, a citizen of the United States, residing at 345 Fifth Avenue, Parnassus, in the county 5 of Westmoreland and State of Pennsylvania, have invented certain new and useful Improvements in Reenforced Car End-Wall Structures, of which the following is a specification.

10 My invention relates to reenforced car end structures and has for one of its objects to provide a novel sheet metal wall structure, particularly for end walls of railway box cars, which is made up of a number of 15 relatively narrow metal sheets having reinforcing ribs of a form which provides maximum strength and rigidity to resist the various strains to which end structures of railway cars are subjected while in service. The 20 sheets are preferably of the size and the reinforcing ribs are of such form as make it possible to press the sheets on smaller, lighter presses than are required for pressing larger sheets having the type of reinforcing ribs or corrugations commonly used 25 at the present time.

The thrusts of a cargo against the end wall of a car may be of a general character tending to tear the end wall from its attachment with the car frame or they may be of a local character tending to perforate or distort the end panel at some particular point. The point at which the end wall structure is subjected to the greatest thrusts 30 of the cargo, resulting from the sudden starting or stopping of the car, depends largely upon the character of the cargo. If the cargo consists of material in bulk, such, for example, as grain, the cargo thrusts are 35 greater adjacent the vertical center of the end than at points adjacent to sides. If the cargo consists of relatively heavy objects, for example piping, railroad rails or the like, which, due to their weight, do not extend 40 far above the flooring of the car, the lower portion of the end wall is subjected to greater thrusts than the upper portions thereof. I therefore contemplate as one of the objects of this invention to provide a car 45 end structure which will have the necessary strength and rigidity to withstand the general thrusts and stresses due to the shift- 50

ing of the cargo and to also provide the end structure with novel reinforcements, which will resist the various local thrusts of the 55 cargo.

A further object of the invention is to provide an end structure, of the above character, in which the sheets are overlapped at their meeting edges and are provided with 60 novel reinforcing ribs so arranged with relation to each other as to provide the lower portion of the end with greater reinforcement than the upper portion of the car so as to resist the inertia thrusts of the cargo 65 adjacent the flooring of the car. The said reinforcing ribs are so formed as to provide maximum strength adjacent the vertical center of the end so as to withstand the cargo 70 thrusts adjacent the vertical center line of the end.

A further object of the invention is to provide an end panel for railway cars having reinforcing ribs which in addition to strengthening the vertical center portion of 75 the panel are so formed as to provide an effective resistance to the weaving or twisting strains which tend to distort the car from its rectilinear shape. Such strains usually result from the swinging motion of 80 the car due to the roughness of the track or when the car rounds a curve.

The invention is illustrated in a preferred embodiment in the accompanying drawings 85 wherein—

Fig. 1 is an end view, in elevation, of the superstructure of a railway box car showing a reenforced end structure made in accordance with my invention.

Fig. 2 is a plan view partly in section of 90 the structure shown in Fig. 1, the roof boards, sides and end fascias being omitted from this view for the purpose of clearness.

Fig. 3 is a vertical sectional view taken on line 3—3 of Fig. 1 looking in the direction indicated by the arrow. 95

Fig. 4 is a perspective view of the upper sheet used in my preferred construction.

Fig. 5 is a perspective view of one of the intermediate sheets, said view showing the 100 inner face of the sheet.

Fig. 6 is a view in perspective showing the outer face of the sheet illustrated in Fig. 5.

Fig. 7 is a fragmentary sectional view taken through one of the reinforcing ribs on line 7-7 of Fig. 1 and

Fig. 8 is a modification of the structure shown in Fig. 6.

Like characters of reference designate like parts in the several figures of the drawings.

Referring to the drawings, 10 designates 10 the ridge pole, 11 the purlins, 12 the side plates, 13 the corner posts, 14 the end sill, 15 the side sills, 16 the buffer block, 17 the outer side sheathing and 18 the inner lining of the car. The end wall structure of the car 15 is made up of a plurality of relatively narrow metal sheets which are preferably horizontally disposed and formed with reinforcing ribs, which extend across the car from side to side thereof. While I have illustrated and will describe a sheet metal end structure of horizontally disposed sheets having reinforcing ribs which extend across the car, it will be obvious that the sheets might be arranged vertically without departure from the spirit of my invention. The metal end structure consists preferably of an upper sheet 19, a lower sheet 20, and a plurality of intermediate sheets 21-21^a. The meeting edges of the sheets are overlapped 20 and riveted together by rows of rivets 22. The vertical edges of the sheets are provided with attaching flanges 23, which overlap the side walls of the car and are secured to the corner posts by bolts 24. The 25 upper edge of the upper sheet 19 is preferably bent over on diagonal lines to provide a flange 25 which supports the ridge pole 10 and purlins 11, taking the place of the ordinary end plate usually employed. The 30 bending of the sheet 19 on diagonal lines gives the flange 25 a downward slope corresponding to the slope of the car roof and also increases its width toward its extremities which may be attached to the car 35 framing in any suitable or preferred manner. In the drawings I have shown the said extremities attached to the side plates 12 by angular attaching elements 26. The lower edges of the sheets 19-21-21^a which overlap the upper edges of the adjacent sheets 40 are formed with out-pressed reinforcing ribs or flanges 27 providing beams extending horizontally across the end wall. The middle portion of each of these reinforcements 45 is in the form of a web having a free edge, the web being preferably angular in cross section. The said ribs preferably taper in depth toward the side of the car, the tapered ends being pressed to provide hollow 50 or channel shaped portions adjacent the side walls of the car. The lower flange 28 of the channel portion is riveted to the adjacent sheet by rivets 29. The out-pressed rigidifying ribs 27 preferably terminate 55 within the plane of the angular attaching

flanges 23 and the channel portion of said ribs is preferably open at the outer ends.

By providing the lower edges of the metal sheet with reinforcing ribs which have an angle bar configuration adjacent the vertical center line of the end and terminate in channel shaped ribs adjacent the sides of the car an end wall structure is provided which is light, economical of metal and consists of plates readily fabricated by means of relatively small presses and which at the same time is strengthened by reinforcements so placed as to give the structure very great strength and rigidity as against both cargo thrusts and weaving stresses. It may be noted that the central portions of the reinforcing ribs 27 may be made of a greater depth than the end portions without conflicting with the provision of the Interstate Commerce Commission relating to end ladder clearance between adjacent cars.

In order to provide an effective resistance against the heavier cargo thrusts occurring at points adjacent the floor of the car the sheets 21^a at the lower portion of the end structure are preferably narrower than the upper sheets 21 so that the reinforcing ribs 27 will be closer together in this region.

The end wall structure may be provided with an end lining, designated generally at 30, consisting preferably of vertical nailing strips 31, bolted to the end panel as indicated at 32 so as to extend transversely of the rigidifying ribs 27, and of horizontally 100 disposed lining boards 33 which may be nailed or otherwise suitably secured to the nailing strips 31.

The metal sheet illustrated in Fig. 8 of the drawings is different from the form of sheet illustrated in the preceding figures in that the ends of the channeled portions 27^b-27^b of the rigidifying ribs 27^a are closed instead of being open, the attaching flanges 23^a extending for the full width of the sheet 110 and the channeled portions 27^b merging into the sheet at the angle bends providing such flanges. This modified form of the invention is not specifically claimed herein, being the subject matter of a divisional application filed August 21, 1920, Serial No. 405,017.

While I have described my invention in one specific embodiment and a suggested modification, it will be obvious that further modifications might be made in the structure 120 without departure from my invention. I therefore do not wish to be limited to the exact structure shown and described except in so far as specific limitations may appear in the appended claims.

I claim:

1. A sheet metal wall structure for a railway car comprising a plurality of sheets of different widths, having their meeting edges overlapped and the overlapping portion of 130

said sheets each being formed with integral out-pressed rigidifying flanges, the narrower sheets of said structure being arranged at a point adjacent the flooring of the car 5 so that the rigidifying flanges are closer together in the lower part of the wall than in the upper part.

2. A sheet metal end wall structure for a railway car comprising a plurality of metal 10 sheets of different widths, overlapped along their meeting edges and having their lateral edges bent to form flanges which overlap the side-walls of the car the lower edges of the sheets being offset to form rigidifying 15 ribs; the narrower sheets being disposed so as to form the lower portion of the structure and the wider sheets being arranged to form the upper portion thereof so that the rigidifying flanges are closer together in the 20 lower part of the wall than in the upper part.

3. A sheet metal end panel for a railway car comprising a metal sheet formed with a 25 pressed rigidifying rib which for a portion 30 of its length is in the form of a web having a free edge and for the remaining portion is channel-formed.

4. A sheet metal end panel for a railway 35 car comprising a metal sheet formed with an 40 out-pressed rigidifying rib which for a portion of its length is in the form of a web having a free edge and adjacent an end is channel-formed.

5. A sheet metal end panel for a railway 45 car comprising a metal sheet formed with an 50 out-pressed rigidifying rib which at its middle is in the form of a web having a free edge and at its ends is channel-formed.

6. A sheet metal end panel for a railway 55 car comprising a metal sheet formed with an 60 out-pressed rigidifying rib of varying depth which at its middle is in the form of a web having a free edge and at its ends is channel-formed.

7. A sheet metal end panel for a railway 65 car comprising a metal sheet formed with an 70 out-pressed rigidifying rib having its greatest depth adjacent its middle and diminishing in depth toward its end and which 75 is of angle bar configuration at its middle portion and channel-formed at its ends.

8. A sheet metal end panel for a railway 80 car comprising a metal sheet formed with an 85 out-pressed rigidifying rib which terminates within the lateral edges of the sheet and is of angle bar configuration at its middle portion and channel-formed at its ends.

9. A sheet metal end panel for a railway 90 car comprising a metal sheet formed with an 95 out-pressed rigidifying rib which is of angle bar configuration at its middle and has its ends bent on diagonal lines to provide 100 channelled portions.

10. A sheet metal end panel for a railway 105 car comprising a metal sheet formed with a 110

pressed rigidifying rib of angle bar configuration at the middle and having its ends bent over on diagonal lines to provide channelled portions which taper in depth.

11. A sheet metal end panel for a railway 115 car comprising a metal sheet formed with a 120 pressed rigidifying rib which is substantially L-shaped, at its middle portion and substantially channel-shaped at its ends.

12. A sheet metal end wall structure for 125 a railway car comprising a plurality of horizontally disposed sheets the lower edges of 130 which overlap the upper edges of adjacent sheets and are formed with pressed rigidifying ribs which at their middle are in the 135 form of a web having a free edge and at their ends are channel-shaped.

13. A sheet metal wall structure for a railway car comprising a plurality of horizontally disposed sheets the lower edges of 140 which overlap the upper edges of adjacent sheets and are formed with out-pressed rigidifying ribs which are of angle bar configuration and of greatest depth adjacent the 145 vertical center line of the end and terminate in hollow tapering portions adjacent the 150 sides of the car.

14. A sheet metal end wall structure for a railway car comprising a plurality of horizontally disposed metal sheets of various 155 widths, the lower edges of which overlap the upper edges of adjacent sheets and are formed with out-pressed rigidifying ribs which are of angle bar configuration and of greatest depth adjacent the vertical center 160 line of the end of the car and terminate in tapering portions adjacent the sides of the 165 car; the lower portion of said structure being made up of the narrow sheets and the upper portion of the structure being made 170 up of the wide sheets.

15. A sheet metal end panel for a railway 175 car comprising a metal sheet formed with an 180 out-pressed rigidifying rib of angle bar 185 configuration at the middle and having its 190 ends bent over on diagonal lines to provide channel-shaped portions which taper in 195 depth and which are open at their ends adjacent the sides of the car.

16. An end wall structure for a railway 200 car comprising a plurality of metal end 205 sheets overlapped and secured together, and each formed with a single reinforcing rib substantially parallel with the line of joiner of said sheets, the sheets in the region of 210 the end subjected to the severest cargo thrusts being narrower than the other sheets so that the ribs stand closer together in this 215 region.

17. An end wall structure for a railway 220 car comprising a plurality of metal end 225 sheets overlapped and secured together one above the other and each formed with a single, substantially horizontal reinforcing 230 rib, the sheets near the bottom of the end 235

- being narrower than the upper sheets, so that the ribs stand closer together in the lower part of the structure than in the upper part.
- 5 18. An end wall structure for a railway car comprising a plurality of metal end sheets overlapped and secured together one above the other and formed with ribs integral with said sheets, respectively, along the lines of joinder of said sheets, the sheets near the bottom of the end being narrower than the upper sheets, so that the ribs stand closer together in the lower part of the structure than in the upper part.
- 10 19. An end wall structure for a railway car comprising a plurality of metal end sheets arranged one above the other and overlapped and secured together, the lower overlapping edges of said sheets being bent to form reinforcing ribs and the sheets in the lower part of the end being narrower than the upper sheets, so that the ribs stand closer together in the lower part of the structure than in the upper part.
- 15 20. An end wall structure for a railway car comprising a plurality of metal end sheets arranged one above the other and overlapped and secured together, the lower overlapping edges of said sheets being bent to form reinforcing ribs, the remaining portions of said sheets being plane and the sheets in the lower part of the end being narrower than the upper sheets, so that the ribs stand closer together in the lower part of the structure than in the upper part.
- 20 21. An end wall structure for a railway car, comprising a plurality of metal end sheets arranged one above the other and overlapped and secured together and each formed with a single, substantially horizontal, integral rib, the lower sheets being narrower than the upper sheets, so that the ribs stand closer together in the lower part of the structure than in the upper part.
- 25 22. An end wall structure for a railway car comprising a plurality of metal end sheets overlapped and secured together and each formed with a single, integral reinforcing rib, said rib being substantially parallel with the lines of joinder of the sheets, certain of said sheets being narrower than other sheets to bring the reinforcing ribs closer together in the portion of the car end subject to greater stresses.
- 30 23. An end wall structure for a railway car comprising a plurality of metal end sheets overlapped and secured together and formed along their overlapped edges with ribs integral with said sheets, respectively, certain of the sheets being narrower than the other sheets so as to bring said ribs closer together in the region of the end subjected to the greater stresses.
- 35 24. An end wall structure for a railway car comprising a plurality of metal end sheets secured together and each provided with a single projecting reinforcement which said reinforcements are substantially parallel with the lines of joinder of the sheets, the remaining portions of the sheets being plane and certain of said sheets being narrower than the others to bring said reinforcement closer together in the region of the car end requiring greatest reinforcement.
- 40 25. An end wall structure for a railway car comprising a plurality of metal end sheets overlapped and secured together, the overlapped edge portions of the sheets being bent away from the planes of the sheets to form projecting reinforcing ribs, and the extremities only of said ribs being bent toward the plane of the sheets and secured, in each case, to the face of an adjacent sheet.
- 45 26. An end wall structure for a railway car comprising a plurality of metal end sheets overlapped and secured together, the overlapped edge portions of the sheets being bent away from the planes of the sheets to form projecting reinforcing ribs, and the extremities only of said ribs being bent toward the planes of the sheets and provided with flanges secured flatwise, in each case, to the face of an adjacent sheet.
- 50 27. An end wall structure for a railway car comprising a plurality of metal end sheets overlapped and secured together, the overlapped edge portions of the sheets being bent away from the planes of the sheets to form projecting reinforcing ribs, which are of maximum depth at the center of the ribs and shallower toward the ends, the extremities only of which ribs are bent toward the plane of the sheets and are secured, in each case, to the face of an adjacent sheet.
- 55 28. An end wall structure for a railway car comprising a plurality of metal end sheets overlapped and secured together, the overlapped edge portions of the sheets being bent away from the sheets to form projecting reinforcing ribs, the remaining portions of the sheets being plane, and the extremities only of said ribs being bent toward the sheets and secured, in each case, to the face of the adjacent sheet.
- 60 29. An end wall structure for a railway car comprising a plurality of metal end sheets overlapped and secured together, the overlapped edge portions of the sheets being bent away from the planes of the sheets to form projecting reinforcing ribs, the middle portion of the edge of each such rib being free and the ends of the same bent and attached to an adjacent sheet.
- 65 30. An end wall structure for a railway car comprising a plurality of metal end sheets overlapped and secured together, the overlapped edge portions of the sheets being bent away from the planes of the sheets to form projecting reinforcing ribs, the re-

- maining portions of the sheets being plane, the middle portion of the edge of each such rib being free and the ends of the same bent and attached to the adjacent sheet.
- 5 31. An end wall structure for a railway car comprising a plurality of metal end sheets overlapped and secured together, said structure being provided with integral, projecting ribs formed by the metal at the overlapped edges of the sheets, which ribs have free outer edges at their middle portions and are channel-shaped and secured to adjacent sheets at their ends.
- 10 32. An end wall structure for a railway car comprising a plurality of metal end sheets overlapped and secured together, said structure being provided with integral projecting ribs formed by the metal at the overlapped edges of the sheets, which ribs have an angle bar configuration at their middle portions and are channel-shaped and secured to adjacent sheets at their ends.
- 15 33. A sheet metal end wall structure for a railway car comprising a plurality of metal sheets each provided with a projecting reinforcement, said reinforcements being substantially parallel to the lines of joinder of the sheets and certain of said sheets being narrower than the other sheets so as to bring said reinforcements closer together in the region of the end subject to the greater stresses.
- 20 34. A sheet metal end wall structure for a railway car comprising a plurality of metal sheets arranged one above the other and connected together along adjacent edges, each of said sheets being formed with a substantially horizontal projecting reinforcement and the lower sheets being narrower than the upper sheets, so that the reinforcements are closer together in the lower than in the upper part of the structure.

CHARLES D. BONSALL.
